LABEL APPLYING MACHINE

Kenneth Fairford McMinn, Waukegan, Ill., assignor, by means assignments, to New Jersey Machine Corporation, Hoboken, N. J., a corporation of New Jersey

Application October 11, 1939, Serial No. 298,911

5 Claims. (Cl. 216—55)

My invention relates generally to label applying machines, and particularly to label applying machines of the automatic or semi-automatic type.

In the pharmaceutical and other industries, it is necessary to label large numbers of rather small and sometimes fragile containers which may be special shapes, as for example ampoules, dental cartridges, and the like; and the principal object of the present invention is to provide an improved label applying machine for this purpose. Other objects and the various novel features and advantages of the machine of my invention will be made apparent by reference to the accompanying drawings and the following description of one preferred embodiment thereof.

In the drawings:

Figure 1 is a side elevational view, partially in section, of a label applying machine in accordance with the present invention;

Figure 2 is a fragmentary perspective view illustrating diagrammatically the manner in which labels are applied to dental cartridges by the machine illustrated in Figure 1;

Figure 3 is an enlarged side elevational view, partially in section, of the machine of Figure 1;

Figure 4 is an enlarged perspective view of a portion of the guide and container moving means forming a part of the machine illustrated in Figures 1 and 3;

Figure 5 is a sectional view taken on the general line 5—5 of Figure 4;

Figure 6 is a sectional view taken on the general line 6—6 of Figure 7;

Figure 7 is a sectional view taken on the general line 7—7 of Figure 5;

Figure 8 is a sectional view taken on the general line 8—8 of Figure 5; and

Figure 9 is a fragmentary sectional view taken on the general line 9—9 of Figure 3. This view illustrates the operation of the mechanism which is utilized for pressing the labels in place on the containers to which they are applied.

The label applying machine illustrated in the drawings includes a box-like frame 11, preferably of cast or fabricated metal construction, which serves as the main support for the various structural elements of the machine; the exact details of the frame 11 are not of particular importance so far as the present invention is concerned. A main drive shaft 13, which is normally rotated at uniform speed, is supported on the frame 11 in a horizontal position by means of suitable bearings, not shown. This shaft 13

supports and rotates a cam 15 which serves as the principal operating member for the container feeding portion of the apparatus.

The label applying mechanism proper is supported upon the main frame 11 adjacent the upper end thereof. This mechanism includes a combined container guide and feeding means 17 which is affixed to the main frame 11 by means of a suitable angle iron bracket 19, and a label conveying mechanism 21 which is operable to 10 convey labels to the containers which are moved into position by the container guide and feeding means 17. Since the apparatus illustrated in the drawings was designed particularly for use in applying labels to dental cartridges, which 15 articles, as illustrated in Figure 2, comprise a hollow, cylindrical glass tube 23 about 3 inches long and $\frac{1}{8}$ of an inch outside diameter for containing a liquid medicament and two stoppers 25 for closing the ends of the tube, the guide and 20 feeding means 17 and the label conveying and applying mechanism 21 have been designed particularly for use in conjunction with elongated cylindrical containers. It will be understood, however, that by suitable changes in the form 25 and proportions of the various elements, the machine may be adapted for the applying of labels to containers of other types and shapes.

The particular details of the label conveying mechanism 21 which operates to convey labels 30 into proximity with the cartridge containers located on the container guide and feeding means 17 are not important features of the present invention, and various known types of label conveying apparatus may be used. Vacuum type 35 mechanisms are, however, particularly satisfactory for this purpose and their use is recommended. This apparatus as will hereinafter appear is arranged to apply labels to two cartridges simultaneously, and includes (see Figure 40 3) two magazines 26 arranged side by side for holding two stacks of the labels 27 which are to be applied to the cartridges, a hollow label carrier member 29 having two spaced label supporting heads 31, and suitable operating means. 45

During each label applying operation of the machine the label carrier member 29 is moved so as to bring the two label supporting heads 31 into proximity with the two stacks of the labels 27 contained in the label magazines 26, this position being indicated by the dotted outline of the member 29 appearing at the right hand side of Figure 3. While in this position suction is applied to each of the heads 31 through a pipe 33, and this suction causes the uppermost label from 50 55

each stack to move toward, and to adhere to, the lower face of the adjacent label supporting head 31. Thereupon the operating means for the label carrier member 29 moves that member 5 from the position indicated by the dotted outline at the right hand side of Figure 3 to the position indicated by the full lines at the left hand side of that figure. During this movement the two labels 27 which are held against the 10 heads 31, are carried over a glue applying roller 34 which is continuously rotated at proper speed in contact with a second roller 35 which dips into a reservoir 37 containing liquid glue 39 of suitable character. By this operation glue is 15 applied to each set of labels as those labels are moved from the label magazines 26 into the label applying position overlying the guide and feeding means 17.

The combination guide and feeding means 17 20 which operates in conjunction with the label conveying mechanism 21 is illustrated particularly in Figures 4 through 8, and includes a flat base or frame 41 which is supported in a horizontal position upon the bracket 19. The upper 25 surface of the guide frame 41 is provided with two V-shaped grooves or guide slots 43, along which the cartridge containers are moved during the operation of the machine. As pointed out previously, the machine illustrated in the 30 drawings is arranged to apply labels simultaneously to two cartridges, and accordingly is provided with two of the guide slots 43. It will be understood, however, that the number of guide slots is dependent solely upon the rate at which 35 the unmarked containers can be fed to the machine, and if desired, labels can be applied simultaneously to as many containers as may be desired.

The feeding mechanism for moving the cartridges along the guide slots 43 includes a pair 40 of pusher members 45 which are connected together for simultaneous movement by means of a cross head 47. The cross head 47, in turn, is connected to a cylindrical operating member 49 45 which moves within a cylindrical guide passageway 51 formed in the frame 41. To prevent binding of the member 49 during its movement within the guide passageway 51, a guide rod 53 of relatively small diameter is connected to 50 the member 49 and is arranged to move within a second cylindrical guide passageway 55 formed adjacent to the inner end of the frame 41, as illustrated particularly in Figure 6.

The interconnected pusher members 45, the 55 cross head 47, and the cross head operating member 49 are moved backward and forward during the operation of the machine by means of a link 57 and a bell crank 59 which is supported upon the frame 11 by a suitable bearing 61, as illustrated particularly in Figures 1 and 2. One end of the link 57 is bifurcated (see Figure 7) and is pivotally connected to a downwardly extending projection 63 formed integrally with the cross head operating member 49, and the other end 60 of the link 57 is pivotally connected to the upper end of the bell crank 59. The lower end of the bell crank 59 is provided with a cam follower 65 which rides over the operating cam 15 for the feeding mechanism.

To prevent jamming of the machine during its 70 operation and possible injury to the cartridges or other containers being labeled, forward movement of the interconnected pusher and cross head members 45 and 47 is accomplished by means of 75 springs such as are illustrated at 67 in Figure 1

which serve to hold the cam follower 65 in contact with the surface of the cam 15. This arrangement permits convenient adjustment and control of the amount of forward movement through the use of an adjustable stop, such as is 5 illustrated at 69, or the like, and also provides a positive return for the pusher members and cross head.

During the operation of the machine, two unlabeled cartridges, a supply of which may conveniently be contained in a container 71 supported upon the supporting bracket 19 for the guide and feeding means 17, are placed in the guide slots 43 at a time when the pusher members 45 are in a fully retracted position (see Figures 1, 4, 5 and 6). As the drive shaft 13 rotates the cam 15 to bring the sector A (Figure 1) into engagement with the cam follower 65, the interconnected pusher members and cross head 45 and 47 are moved to the right as illustrated in Figure 3, thereby moving the two cartridges which have previously been located in the guide slots 43 from the feeding position of Figures 1, 4, and 5 to the labeling position of Figure 3, in which position the labels are applied.

In order to hold the cartridges stationary during the label applying operation, the apparatus includes a pair of rubber surfaced rollers 73 which are vertically adjustably supported upon a suitable horizontal shaft 75 which extends 30 crosswise of the frame 41 for the guide and feeding means 17. Rather close adjustment of the pressure exerted by the rollers 73 is necessary in order to secure good operation of the machine, and for this reason the bearing supports for the 35 roller supporting shaft 75 comprise a pair of bell crank levers 77 which are hingedly connected at one end to the frame 41 by suitable bolts 79 so as to permit the roller and shaft assemblage to be swung toward or away from the frame 41. It is desirable that the support means for the 40 shaft 75 include a locking means such as the screws 81 for locking the rollers 73 in position.

Immediately following each forward movement of the interconnected cross head and pusher members, those members are returned to the retracted position of Figures 1, 4, and 5, the return movement being effected by the sector B of the cam 15. The cross head and pusher members 47 and 45 are then held in this retracted position 50 for a sufficient period of time to permit the operator to place two additional cartridges in the guide slots 43, this stationary period being accomplished by the arcuate section C of the cam 15.

During the forward or feeding movement of the cross head 47 and the pusher members 45, the label applying mechanism is operated to remove a label from each of the stacks contained in the magazines 26 and to convey these labels over the 55 glue applying roller 34, so that at about the time the retraction of the cross head and pusher members begins, the label carrying member 29 is in the position illustrated by the full lines in Figure 3. Thereupon, the label carrier member is moved vertically downward so as to bring each of the labels 27 carried on the heads 31 in contact with one of the cartridges as illustrated in Figure 3. This movement is also illustrated diagrammatically in Figure 2 wherein the two positions of 70 the labels 27 are indicated by dotted lines. The suction is then removed from the heads 31 and the label carrier member 29 is raised and immediately retracted in the direction of the magazines 26.

Simultaneously with the retraction of the label carrier member 29, the mechanism for pressing the labels into contact with the outer surface of the cartridge tubes comes into operation. Essentially, this mechanism comprises nothing more than two sponge rubber pads 83 which are supported upon a suitable yoke member 85. The yoke 85 is operated, by means which is not shown, to move the pads 83 downwardly from the position of Figure 3 to the position of Figure 9, following each operation of the label carrier member 29, whereby the two glued labels 27 which have been previously positioned upon the cartridge tubes 23, as illustrated in Figure 8, are pressed into engagement with the underlying cartridge tubes 23. The yoke 85 and the two presser pads 83 carried thereon are then raised to the normal position of those members which is illustrated in Figures 1 and 3. By the time 10 the label pressing means has been raised to the position of Figure 3, the cam 15 will have been rotated almost to the beginning of sector A, and the machine will be ready to repeat the sequence of operations previously described.

25 The forward movement of the two cartridges which were placed in the guide slots 43 during the label applying operation just described serves to push forward the two cartridges to which the labels have been applied and these cartridges 30 drop into a suitable guide as illustrated at 81 in Figures 1 and 3, from which they may be carried away by a conveyor belt or the like. Once initiated, the operation of the machine takes place practically automatically, it being necessary merely for the operator to position two of the cartridges in the guide slots 43 following after retraction of the interconnected cross head and pusher members 47 and 45. Each forward movement of the unlabeled cartridges placed in 35 the guide slots 43 by the operator automatically effects the removal from the mechanism of the labeled cartridges. Jamming of the machine or breakage of containers is positively prevented and in actual operation the machine has proven 40 most satisfactory. In fact it has been found possible for a single operator to label upwards of 20,000 cartridges a day by use of the machine.

45 From the foregoing it will be seen that I have provided an improved automatic labeling machine for applying labels to small or irregularly shaped containers, the particular machine illustrated in the drawings and described herein being especially suited for applying labels to elongated cylindrical containers such as dental cartridges or the like. The apparatus of my invention utilizes a minimum of structural elements, and at the same time it is positive and dependable in operation and is substantially foolproof. It will be apparent to those skilled in the art that 50 various machines may be developed embodying the principles of my invention. Accordingly, it is my desire that the accompanying claims shall be accorded the broadest reasonable construction consistent with the language appearing 55 therein and the prior art.

I claim the following as my invention:

1. In a label applying machine of the class described, a guide for directing the movement of the articles which are to be labeled, an intermittently operated, reciprocating pusher member for moving the articles to be labeled along said guide, in sequence, from an initial feeding position to a labeling position, means for holding each article which is moved to said labeling position so as to permit a label to be applied thereto,

means for holding a supply of labels, label conveying means operable following the movement of each article to be labeled to said labeling position to remove a label from said supply, apply glue to one surface of said label, and place said glued label on the article held in said labeling position, and presser means operable following each operation of said label conveying means to press said glued label into engagement with the article then in said labeling position. 10

2. In a label applying machine of the class described, a guide for directing the movement of the articles which are to be labeled, an intermittently operated, reciprocating pusher member for moving the articles to be labeled along said guide, in sequence, from an initial position adjacent one end of said guide to a labeling position adjacent the other end of said guide, resilient means for holding each article which is moved to said labeling position so as to permit a label to be applied thereto, means for holding a supply of labels, label conveying means operable following the movement of each article to be labeled to said labeling position to remove a label from said supply, apply glue to one surface of said label, and place said glued label on the article held in said labeling position, and presser means operable following each operation of said label conveying means to press said glued label into engagement with the article then in said labeling position, 20 thereto, means for holding a supply of labels, label conveying means operable following the movement of each article to be labeled to said labeling position to remove a label from said supply, apply glue to one surface of said label, and place said glued label on the article held in said labeling position, and presser means operable following each operation of said label conveying means to press said glued label into engagement with the article then in said labeling position, 25 said guide and pusher member being so arranged that the forward movement of each unlabeled article from said initial position to said labeling position causes the previously labeled article to be pushed out of the machine. 30

3. In a label applying machine of the class described, a guide means which is provided with a guideway for directing the movement of the articles which are to be labeled, a pusher member arranged to be moved intermittently between a retracted position and an advanced position, said pusher member being operable to move the articles to be labeled along said guideway, in sequence, and each movement of said pusher member from said retracted position to said advanced position causing one of the articles to be labeled to be moved from an initial position adjacent one end of said guideway to a labeling position, means resiliently biasing said pusher member toward said advanced position, means for intermittently returning said pusher member from said advanced position to said retracted position, means for holding each article which is moved to said labeling position so as to permit a label to be applied thereto, and means including a label conveying member and label presser member for applying a glued label to each article while it is held in said labeling position. 40

4. In a label applying machine of the class described, a guide means which is provided with a guideway for directing the movement of the articles which are to be labeled, a pusher member arranged to be moved intermittently between a retracted position and an advanced position, said pusher member being operable to move the articles to be labeled along said guideway, in sequence, and each movement of said pusher member from said retracted position to said advanced position causing one of the articles to be labeled to be moved from an initial position adjacent one end of said guideway to a labeling position adjacent the other end of said guideway, spring means resiliently biasing said pusher member toward said advanced position, means including a cam and a linkage intermediate said cam and said 45

- pusher member for intermittently returning said pusher member from said advanced position to said retracted position, means including an adjustably supported roller for holding each article which is moved to said labeling position so as to permit a label to be attached thereto, and means including a label conveying member and a label presser member for applying a glued label to each article while it is held in said labeling position, said guide means and said pusher member being so arranged that the movement of each unlabeled article from said initial position to said labeling position causes the previously labeled article to be pushed out of the machine.
5. In a label applying machine of the class described, in combination, a guideway for directing

the movement of the articles which are to be labeled, reciprocatory means for moving said articles along said guideway from an initial feeding position to a labeling position, means for holding each article which is moved to said labeling position on said guideway so as to permit a label to be applied thereto, means for holding a supply of labels, label conveying means operable to remove a label from said label supply, apply glue to one surface of said label, and place said glued label on the article held in said labeling position, and presser means operable following each operation of said label conveying means to press said glued label into engagement with the article then in said labeling position.

KENNETH FAIRFORD McMINN.
